CLAIM

The ornamental design for a game board with set of game pieces, as shown and described.

DESCRIPTION

1. Game board with set of game pieces

Fig. 1.1 is a top perspective view of the game board with set of game pieces in accordance with the present design; Fig. 1.2 is another top perspective view thereof;

Fig. 1.3 is another top perspective view thereof;

Fig. 1.4 is a front elevation view thereof;

Fig. 1.5 is a back elevation view thereof;

Fig. 1.6 is left side elevation view thereof;

Fig. 1.7 is a right side elevation view thereof;

Fig. 1.8 is a top plan view thereof;

Fig. 1.9 is a bottom plan view thereof;

Fig. 1.10 is a front elevation view of the game pieces of the game board with set of game pieces, shown separately for clarity of illustration;

Fig. 1.11 is rear elevation view thereof;

Fig. 1.12 is a left side elevation view thereof;

Fig. 1.13 is a right side elevation view thereof;

Fig. 1.14 is a top plan view thereof; and

Fig. 1.15 is a bottom plan view thereof.

(Continued)

The characteristic features of the design lie in the shape of the game board and game pieces as shown.
